DESIGN FOR A GLASS BOTTLE

William J. Lundy, Olean, N. Y., assignor to Olean
Glass Company, Olean, N. Y., a corporation of
New York

Application April 9, 1940, Serial No. 91,557

Term of patent 7 years

To all whom it may concern:

Be it known that I, William J. Lundy, a citizen of the United States and residing at Olean, in the county of Cattaraugus and State of New York, U. S. A., have invented a new original, and ornamental Design for a Glass Bottle, of which the following is a specification, reference being had to the accompanying drawing, forming a part thereof, wherein:

I claim:

The ornamental design for a glass bottle, substantially as shown.

WILLIAM J. LUNDY.
